UNITED STATES PATENT OFFICE

ROBERT E. KOCHS, OF CHICAGO, ILLINOIS, ASSIGNOR TO THEO. A. KOCHS COMPANY, OF CHICAGO, ILLINOIS, A CORPORATION OF ILLINOIS

RECLINING CHAIR

Application filed May 26, 1930. Serial No. 455,599.

This invention relates to improvements in reclining chairs, and has particular reference to a novel locking means, operated by a foot control, for holding certain units of the chair in a selected position of adjustment. The principal object of this invention is to provide in connection with such locking means a treadle control therefor operable conveniently from opposite side of the chair; and to so construct the lock and its operating parts as to maintain the adjustable chair units immovably in any desired position.

These and other objects, as will hereinafter appear, are accomplished by the present construction which is fully described in the following specification and shown in the accompanying drawings, in which—

Figure 1 is a perspective view of a chair, such as is adapted for service in a beauty parlor;

Fig. 2 is an enlarged vertical section through the base of the chair with the back, arms, seat, and apron removed, the locking mechanism being shown in elevation;

Fig. 3 is an enlarged vertical section of the locking mechanism, viewed as shown in Fig. 2; and

Fig. 4 is a transverse sectional view of the locking mechanism taken as indicated on line 4—4 of Fig. 3.

In the embodiment illustrated, A designates a suitable chair base upon which is pivotally mounted at 5 a back B. A cushion C is removably supported on the base, as is also an adjustable apron D pivotally mounted at 6 near its front edge. Arm rests E may be pivotally connected to the back at 7 and similarly connected at 8 to extensions 9 running up from the apron D. By reclining the back 10 the apron will be simultaneously raised through the arm rest connections just described.

The back and apron are secured in any desired position by locking mechanism which, as shown, comprises a bar 10 pivotally connected at its forward end to the apron as shown in Fig. 2. This bar extends, by preference, toward the rear of the chair and substantially in its center. The base may be provided with a transverse support 11 from

which depends a bracket 12 in the form of an inverted U (see Fig. 4). A transverse shaft 13 which is carried in suitable bearings in the bracket extends substantially the width of the base, and has in its center a flat 14 cut to a desired depth. The bar 10 and transverse shaft 13 intersect within the extensions of the bracket 12, at which point the body 15 of the locking mechanism is supported. This body is provided with depending side walls 16 which are connected at their outer ends, and adjacent one edge, to form a socket 17. The body is further provided with a bore 18 to slidably receive the bar 10, and with a transverse bore 19 extending through the walls 16, to receive the transverse shaft 13.

An opening 20 through the body and in communication with the bore 18 is adapted to receive a shoe 21, one edge of which is convexly formed to fit the bar 10. A lever 22, having a socket 23 at one end and a cam 24 at its opposite end, is mounted on a pin 25 between the walls 16 of the body, and fitted into the slot formed by the flat 14 of the transverse shaft. A coil spring 26 confined within the sockets 17 and 23 exerts an upward pressure on the lever 22 causing the cam 24 to bear against the shoe which thereupon engages the bar 10 to secure it against sliding movement in the body.

The clutch is operated by one or more foot pedals 27, each having a lever 28 extending therefrom to be pivotally supported in a bracket 29 which may be mounted on a cross brace 30 of the chair base. Secured to each end of the transverse shaft 13 is a crank arm 31. Links 32 connect the extreme ends of the lever 28 and the crank arms 31, so that downward movement of one of the pedals 27 will rock the transverse shaft 13, as shown in Fig. 2, in a clockwise direction; by this movement one of the edges of the flat 14 is brought into contact with the lever 22 forcing its outer end downwardly against the tension of the spring 26 and releasing the pressure of the cam 24 against the shoe 21. When the pressure of the shoe against the bar 10 is thus released, the bar may be moved longitudinally in the bore 18 to permit ad-

justing movement of the back and apron of the chair.

It will be seen that the body of the rocking mechanism is capable of rocking within the bracket 12 to follow the movement of the bar 10, one end of which moves in an arc about the pivot point 6. To prevent the lever 28 and the link 32 from passing their center, a pin 33 secured in the end of the lever 28 is adapted to bear against the junction of the forked end of the link 32 before the center is reached.

The present locking mechanism and control means therefore is advantageous in the respects of simplicity of construction, facility in operation, and dependability in service. It is to be observed that the pedal control, as shown, is of duplex character; the location of the treadles being, by preference, near opposite sides of the chair; and in operation one or both hands of the attendant are free to raise or lower the back, as desired. The lock, while acting frictionally to sustain the parts in a selected adjustment, operates very effectively in the accomplishment of this end in every position to which the parts are movable. Because of these characteristics the chair herein shown and described is meritorious to an unusual degree.

30. I claim:

1. In combination with a chair having an adjustable back and apron pivotally mounted on the chair frame with linked connections therebetween, a bar pivotally connected at one end to the apron, a lock body having a bore receiving the bar, locking means in the body for gripping the bar, a transverse rock shaft supported from the chair frame and extending through said body, providing at 35 a pivotal support therefore, lock holding means interposed between said rock shaft and locking means, and a foot pedal operatively connected to the transverse rock shaft for actuation thereof to release said holding and locking means.

2. In combination with a chair having an adjustable back and apron pivotally mounted on the chair frame with linked connections therebetween, a bar pivotally connected to the apron, a lock body having a bore receiving the bar and an opening extending into the bore, a shoe freely fitted in the opening and adapted to engage with the bar, a treadle operated transverse rock shaft extending 40 through the body and having supporting means connected to the chair frame, a cam journaled in the body and engaging the shoe to force it into engagement with the bar, a lever connected to the cam, and means on the transverse rock shaft for operating the lever to release the shoe from engagement with the bar.

In testimony whereof, I have hereunto set my hand this 1st day of May, 1930.

ROBERT E. KOCHS.
